BY
Chas. F. Clegg
—ATTORNEY

UNITED STATES PATENT OFFICE.

JOHN L. CARTER, OF BROOKLYN, NEW YORK.

HEAT DISTRIBUTER AND EQUALIZER FOR COOKING-STOVES.

1,173,556.

Specification of Letters Patent. Patented Feb. 29, 1916.

Application filed January 13, 1916. Serial No. 71,841.

To all whom it may concern:

Be it known that I, JOHN L. CARTER, a citizen of the United States, and a resident of Brooklyn, in the county of Kings and State of New York, have invented certain new and useful Improvements in Heat Distributers and Equalizers for Cooking-Stoves, of which the following is a specification.

10 The invention pertains more particularly to a novel structure to be placed on the top of a cooking stove to receive thereon vessels in which food is to be cooked or water or the like boiled and which structure serves to 15 distribute and equalize the heat at the bottoms of such vessels and prevents the flames and direct heat from impinging against the same. With the use of my invention, the cooking may be efficiently performed, the 20 danger of burning or scorching the food is greatly lessened and the cooking-vessels are protected against destructive action of the flames.

25 The structure of my invention will preferably be formed from one integral piece or plate of sheet metal folded to afford a proper base to rest on a stove and suitable supports to receive the cooking utensils and also suitable heat equalizing and distributing 30 chambers, all as hereinafter described in detail.

Referring to the accompanying drawings: Figure 1 is a top view of a structure embodying my invention; Fig. 2 a sectional view of the same taken on the dotted line 35 2—2 of Fig. 1; Fig. 3 a sectional view of the same taken on the dotted line 3—3 of Fig. 1; Fig. 4 an enlarged sectional view through a portion of the same; Fig. 5 a sectional view 40 illustrating a modified form of my invention, and Fig. 6 is a further sectional view illustrating another modified form of my invention.

45 The structure of my invention may for convenience be termed a plate, and this plate is formed by bending a sheet of metal of appropriate size into corresponding base members 10 to rest on a stove, upper members 11 affording a support for the cooking vessels, 50 return members 12 above said base members and extending over flame apertures 13 therein, and members 14 connecting said return members and superposed above and spanning the space between the adjoining edges 55 of the same.

In the formation of the plate commencing, say, at the left hand side of Fig. 3, a portion

of the sheet is left to constitute a portion of a horizontal member 14, and thereupon the sheet is bent downwardly and then toward the left suitably below said member 14 to form the return member 12, whence the sheet is bent downwardly and then horizontally toward the right to form a base member 10, at whose right hand edge the sheet is bent upwardly and then downwardly to create a support 11, and then the sheet is bent horizontally toward the right to form another base member 10 and then upwardly and then toward the left to create a return member 12, at whose left hand edge the sheet is bent upwardly and then toward the right to form a connecting member 14 and then downwardly and then toward the left to provide another return member 12, whence the sheet is bent downwardly and then toward the right to form another base member 10 and then upwardly and then downwardly to create another vessel support 11, whence the bendings of the sheet are continued to form 80 as many additional members 10, 12, 14 and 11 as the desired dimensions of the plate may require. Between the base members 10 and return members 12 are formed channels 85 15 for the flow of the heat along the length of the plate and between the return members 12 and top members 14 are formed further heat channels 16, these being above the channels 15, and between the adjacent ends of the members 12, 14 are formed channels or 90 passages 17 which are adjacent to the supports 11 and open from the heat channels 15, said passages 17 serving to direct the heat issuing from the channels 15 upwardly along the vertical portions of the supports 11 and to 95 the cooking utensil which may be resting on the supports 11. The apertures 13 in the base members 10 are below the return members 12 and out of the vertical plane of the passages 17, and hence flames and heat of 100 undue intensity ascending through the apertures 13 will strike the lower surfaces of the return members 12 and be by them directed horizontally and laterally, so that the proper heat will escape upwardly through 105 the passages 17 and against the cooking utensil that may be on the supports 11. The air within the channels 16 becomes heated, and hence the top members 14 are kept hot and the heat radiating therefrom assists in 110 the cooking.

My invention has for its purpose to distribute and equalize the heat arising from the stove and to protect the cooking utensils

against destructive action of the flames and heat of the stove, and these purposes are accomplished by the plate illustrated in Figs. 1 to 4 inclusive.

- 5 The bendings of the sheet metal to form the plate of my invention and the location of the heat apertures 13 may be modified, and hence in Fig. 5 I illustrate a construction exactly the same as that shown in Fig. 10 4 with the exception that the heat apertures are located in the return members, as at 18. In the use of the plate having the apertures 18 in the return members, the heat descends into the channels 15 and finally 15 reaches the passages 17 and ascends along the sides of the support 11.

In Fig. 6 the modification resides in forming extended surfaces 19 for supporting the cooking utensils and in locating some of 20 the inlet apertures for the heat and flames in the base members of the plate and others in the return members. The extended supporting surfaces 19 for the cooking utensils are at the upper ends of the vertical members 20, as clearly shown, and their presence creates additional passages 21 between the top members 22 and the bottoms of the supports. The members 22 correspond with the members 14 of Fig. 3, and since Fig. 6 shows 30 a modification, I number the return members 23, the base members 24 and the inlet apertures for heat 25. I prefer the construction shown in Figs. 1 to 4 inclusive, since in many instances it is desirable that 35 the supports for the cooking utensils be narrow at their upper edges.

In all the forms of the invention hereinbefore described, the sheet of metal is folded to form the long channels, as 15, 16, with the 40 top members 14 and return members 12 separated from the utensil supports sufficiently to form the passages 17, and in each form of the invention the heat inlet apertures or holes, as 13, have over them horizontal members which serve to deflect the heat and 45 flames and prevent the flames and intense heat from passing directly into contact with the utensils which may be placed upon the plate.

50 I am aware that the sheet of metal may be folded in other ways to create long channels and provide members to prevent the flames and intense heat from striking the cooking utensils, and therefore I do not 55 limit the invention to the precise bendings of the sheet of metal hereinbefore described. I have however shown in the drawings the preferred embodiments of my invention and I have found that in practical use the construction shown in Figs. 1 to 4 inclusive is 60 of very great efficiency.

The plate hereinbefore described has been referred to as a top plate for stoves. It is

to be understood however that the same plate may be used as the bottom plate for a 65 portable oven for gas or oil stoves, and therefore my invention is not to be confined to the placing of the plate on top of the stove as distinguished from employing it as the bottom plate for a portable oven. 70

What I claim as my invention and desire to secure by Letters-Patent, is:

1. A heat distributor and equalizer for cooking stoves, comprising a folded plate of sheet metal affording base members, vertical 75 supporting members extending upwardly between said base members, horizontal connecting members at the sides of said vertical members and spaced therefrom to form heat passages, and return members between said base members and connecting members and spaced therefrom to form heat channels at the sides thereof, flame or heat openings being formed in some of said members below 80 said connecting members. 85

2. A heat distributor and equalizer for cooking stoves, comprising a folded plate of sheet metal affording base members, vertical supporting members extending upwardly between said base members, horizontal connecting members at the sides of said vertical members and spaced therefrom to form heat passages, and return members between said base members and connecting members and spaced therefrom to form heat channels at 90 the sides thereof, flame or heat openings being provided in said base members below 95 said return members and out of the vertical planes of said heat passages.

3. A heat distributor and equalizer for 100 cooking stoves, comprising a folded plate of sheet metal affording base-members, utensil supporting members, and horizontal members above said base members and spaced therefrom to form heat channels and also 105 spaced from said supporting members to form heat passages, said base-members having openings therein.

4. A heat distributor and equalizer for 110 cooking stoves, comprising a folded plate of sheet metal affording base-members, utensil supporting members, and horizontal members above said base members and spaced therefrom to form heat channels and also 115 spaced from said supporting members to form heat passages, said base-members having openings therein below said horizontal members and out of the vertical planes of said heat passages.

Signed at New York, in the county of 120 New York and State of New York, this 12th day of January, A. D. 1916.

JOHN L. CARTER.
